UNITED STATES PATENT OFFICE.

CLAUDE D. CLARK, OF NEW BRITAIN, CONNECTICUT.

BARREL-MAKING MACHINE.

1,130,888.

Specification of Letters Patent.

Patented Mar. 9, 1915.

Application filed June 13, 1912. Serial No. 703,577.

To all whom it may concern:

Be it known that I, CLAUDE D. CLARK, a citizen of the United States, residing at New Britain, in the county of Hartford and State of Connecticut, have invented certain new and useful Improvements in Barrel-Making Machines, of which the following is a specification.

My invention relates to improvements in barrel making machines and the object of my improvements is simplicity and economy in construction and convenience and efficiency in use.

In the accompanying drawing:—Figure 1 is a side elevation of my improved barrel making machine. Fig. 2 is an elevation of the left end of the same. Fig. 3 is an elevation of the right end of the same. Fig. 4 is a sectional view on the line $\alpha\alpha$ of Fig. 8. Fig. 5 is a fragmentary view of the same with the stave tray tilted upward. Fig. 6 is a plan view of the stave tray. Fig. 7 is a view similar to Fig. 1, with the parts in position for use. Fig. 8 is a similar view of the same with a completed barrel. Fig. 9 is a plan view of the same with the parts in position for the removal of the barrel. Fig. 10 is an end view of the collapsible drum, the shaft being shown in section. Fig. 11 is an end elevation of one of the sectors. Fig. 12 is a sectional view of the same on the line yy of Fig. 13. Fig. 13 is a side elevation of the same. Fig. 14 is a similar view of the segment. Fig. 15 is a similar view of the arm for the same. Fig. 16 is a rear elevation of the segment. Fig. 17 is a sectional view of the same on the line zz of Fig. 13. Fig. 18 is a sectional view of the machine on the line $\alpha\alpha$ of Fig. 8, the movable horns and the arms supported thereby, being shown in the dropped position.

My barrel making machine A comprises a frame B having a pair of side frames 15 cross-connected at the bottom by a bottom strip 16 and at the top by a top strip 17, and forming mechanism C housed therein suitable for receiving the staves 18 and forming and assembling them suitably to compose the barrel D, and trussing mechanism E suitable for trussing the barrel D for receiving the hoops F. A main shaft G is rotatively mounted in end bearings supported by the

side frames 15 comprising a right bearing 19 and a left bearing 20 and is composed of two parts, respectively a main part 21 at 55 the left and which extends the greater part of the distance between the side frames 15 and a right part 22 which completes the distance, the ends being normally in abutment as shown at 23, Fig. 1, and are operatively coupled together by the sliding sleeve 24 operated by the right lever H. A link 25 on the lever H and a pin 26 on the sleeve 24 serve to connect the said lever and sleeve. The left bearing 20 has the outer end provided with a hinge connection 27 that permits swinging the left shaft part 21 on a vertical axis and bringing the free end away from the position of abutment with the right shaft part 22 and clear of the same so as to 60 permit of removing the finished barrel D longitudinally and axially from the left or main shaft part 21. A horizontal platform 28 may be provided on the left frame 15 adjacent to the hinge connection 27 suitable 65 for coöperating with a shoe 29 provided on the bearing 20 to support part of the weight of the shaft part 21 and the load and relieve the hinge connection 27 during the operation of removing the barrel D. A collapsible drum I is mounted at approximately 70 the middle portion of the shaft G and comprises two sector members J. The two sector members J are similar, except that in use one is a left and the other a right, and they comprise each a pair of sectors 30 operated by a modified umbrella mechanism comprising a collar 32 fixedly mounted on the shaft G to which the inner ends of sectors 30 are pivotally connected, a sleeve 31 is 75 slidably mounted on the shaft G and links 33 connecting the sleeve 31 and the outer portions of the sectors 30. A latch 34 mounted on the sleeve 31 engages with a hole in the shaft G and serves to hold the sleeve 80 31 in proper position to hold the sector members J extended. A spring 36 mounted on the shaft G bears with the inner end against the fixed collar 32 of one sector member J and the sliding sleeve 31 of the other member 85 and operates to collapse the drum I when the latch 34 is disengaged by forcing the sleeve 31 outward. 90

Lever arms H serve to distend the drum I

by operating the sector members J, being pivotally connected by their lower ends to the bottom cross-bar 16 and having the upper ends 37 extending above the top of the machine suitably for being manipulated, and the intermediate portions engage with the sleeves 31. The left lever H engages directly with the left sleeve 31 and the right lever H is connected to the coupling sleeve 24 as described and which latter as it is moved along inwardly to the coupling position abuts with the right sleeve 31 and forces the same to the position for engagement of the right latch 34. The sector 30 is a T shaped structure comprising an arm 38 that is connected as described to the collar 32 and the links 33 and the segment 39 resiliently supported at the outer free end thereof and having an outer periphery 40 in the form of an arc of approximately 90 degrees and of a diameter approximately that of the diameter of the interior of the barrel D.

As the sector 30 is not in a strictly radial position relatively to the shaft G when the drum I is in extended position I provide a kink or angular bend in the arm 38 as shown at 41 or the equivalent thereof in providing the outer end thereof with a head 42 which has the outer periphery finished off plane suitably to form a platform 47 for receiving the segment 39 when the latter is directed in a radial plane when in normal position for use. The head 42 overhangs the arm body 43 laterally, is connected on the lateral ends with the links 33 by means of screws 44 or the equivalent, has a pair of radial holes 45 to receive guide pins 46 and on the outer periphery the platform 47 may be counter-bored as shown at 48 concentric with the holes 45 to provide a housing for the inner end of the coil springs 49.

The segment 39 comprises the outer periphery 40 referred to in the form of an arc and the chord base 50, which latter is preferably recessed as shown at 51 at the middle to receive the head 42 and connected parts and holes 52 for fixedly receiving the guide pins 46 on which the coil springs 49 are mounted. The guide pins 46 pass through the holes 45 and have the outer ends engaged with the holes 52 and serve to guide the segment 39 relatively to the arm 38, and the springs 49 tend to separate these parts, the amount of separation being limited by the heads 53 of the pins 46 engaging with the head 42 of the arm 38. Slots 54 in the segment 39 in the path of the links 33 serve to receive the same when the drum I is in the collapsed condition and permit free movement of the segment 39 and arm 38 to the extent necessary for opening and closing under normal conditions of usage.

As stated, the sector members J are respectively right and left, each sector mem-

ber J comprising a pair of sectors 30 positioned on diametral opposite sides of the shaft G, whereby the sectors 30 of one sector member J combine with those of the other sector member J to complete the circle.

The resilient connection shown and described for the segment 39 and arm 38 provides for a limited radial varying of the position of the segments 39 and a corresponding leeway in the diameter of the barrel, and consequently permits of a corresponding range in the circumferential distance. This of course permits of some latitude in the total circumferential dimension of the group of staves as the last stave is forced in under pressure in opposition to the resiliency of the springs 49 and these springs 49 will give way furthermore in the wind-lassing or trussing operation, permitting the group of staves to be brought together, with the adjacent edges in abutment.

The collapsible drum I described is positioned suitably for supporting the middle portion of the staves of the barrel D and cooperates with a pair of laterally disposed formers K which engage with the outer surface of the staves. The lateral formers K comprise each a pair of former members respectively a fixed member 55 and a movable member 56 having upper ends in the form of horns 57 that are of suitable dimensions and shape to inclose the barrel space, being separated at the upper ends at the front suitably to admit the staves. The former members 55 and 56 are supported on a common shaft 58 that itself is supported on the end frame 15, and they are held in proper relative position by means of the lower cross connecting strip 16 with which they engage by means of the downwardly projecting arm 59. The movable member 56 is positioned on the outer side of the fixed member 55 for reasons to be explained. The lower arm 59 and the upper arm or horn 57 of the movable former member 56 are in one plane, and the said movable member 56 is pivotally mounted at the junction of the said arms 57 and 59 on the shaft 58, and when in normal position for use the lower arm 59 is in abutment with the bottom cross-connecting strip 16. The fixed former member 55 is similarly mounted on the shaft 58 at the junction of the upper arm or horn 57 and the lower arm 59 and on the inner side of the movable member 56 as mentioned and in abutment therewith, and the upper arm or horn 57 is off-set outwardly at the junction of the two arms as shown at 61 so as to bring the said upper arm 57 opposite the upper arm 57 of the movable former member 56 and the lower arm 59 is fixedly secured to the bottom cross-strip 16 by means of bolts or screws 60. The two upper arms or horns 57 of the two lateral formers K are cross-connected by means of the cross-connecting

rod 62 that serves conveniently as a handle to operate the two movable members 56 together.

A longitudinally and outwardly extending arm 63 is secured to each of the members 55 and 56 adjacent the shaft 58 and on the outer side that serves as a lower stop for part of the windlassing or trussing mechanism E to be described, and near the upper portion of the horn 57 of the former members 55 and 56 is a second arm or pin 83 that serves as an upper stop as a part of the said mechanism. The extreme upper end 65 of the horn 57 of the fixed member 55 overhangs the corresponding extreme or tip end 66 of the horn 57 of the movable arm 56 when in normal position the two ends being separated as usual to provide a mouth through which the staves are fed to the middle former or drum I and the lateral formers K, and the top edge 64 of the horn 57 of the movable member 56 outward from the tip end 66 is formed straight and on a level with the tip end 66 to provide a tray platform to receive and support a stave tray 67.

I prefer to have the tray 67 movable and arranged to be tilted out of the way when not in use and do this by means of a loop 68 of iron wire or rod, and which loop 68 also serves normally to hold the movable members 56 in operative position by engaging with a suitable projection or heel 69 just outside of and below the tray platform 64.

The tray 67 is of sheet metal and comprises an elongated rectangular base or bottom 70 slightly longer than the staves to be supported thereon and suitable for resting on the tray platform 64, has the end edges 71 turned upward and at intervals as shown at 73 a portion of the longitudinal edge 72 is turned downward and looped around the cross-connecting member 74 of the loop 68 to form a hinge connection therewith. The end turned up edges 71 are severed from the base 70 from the inner edge 75 of the base 70 outwardly for an appreciable portion of the length and the free ends 76 are sprung inwardly to provide a resilient engagement with the ends of the staves for guiding the same to the formers. The inner edge 75 of the base 70 is slotted at two places as shown at 77 to permit the base 67 to clear the tip ends 65 of the horns 57 of the fixed member 55 in moving the tray 67 back and forth. The inner ends of the side arms 78 of the loop 68 are provided with eyes 79 suitable for engaging with the windlass shaft 80 and to be pivotally supported thereby. Accordingly, as described, after the movable members 56 have been tilted to the normal operating position by means of the handle rod 62, dropping the loop 68 brings the tray 67 to the platform 64 and at the same time brings the cross-connecting member 74 of the loop 68 into engagement with the notch or heel 69.

and holds the lateral formers K in the closed position. An inward movement of the levers H distends the middle collapsible drum I. When the tray 67 is tilted upward it is retained in upright position by bearing 70 against the top cross connecting strip 17. The tray 67 when in normal position is located suitably to feed the staves therefrom to the mouth referred to between the tip ends 65 and 66 of the horns 57 to the formers I and K.

The trussing mechanism E comprises a pair of trussing members L, positioned on the outer side of the lateral formers K each of which comprises a pair of mating arms 81 having the inner edges of suitable shape and dimensions to inclose the proper space for the barrel and to bring the staves to such shape and dimensions when brought to the closed position by the windlass mechanism 82 provided for operating the same.

Each arm 81 is mounted by the lower end on the shaft 58, and has the upper end connected to the windlass mechanism 82, and is composed of two parts, respectively an upper part 84 and a lower part 85, which parts are connected intermediate the said ends by a pivotal connection 86.

As described the arm 81 is a composite structure, and the lower part 85, connected to the upper part 84 by the pivotal connection 86 serves as the means for connecting the same to the shaft 58. The said lower part 85 contains the hub portion 87 which is somewhat elongated and is provided with a longitudinal slot 88 that is a fit for the shaft 58 and is normally positioned approximately vertically and a branch 89 extends laterally from the upper end of the said hub portion 87. The upper end of the branch 89 overlaps the lower end of the upper part 84. The said overlapping ends are penetrated by the pivotal pin 90 and compose therewith the pivotal connection 86. The slot 88 engaged with the shaft 58 permits of raising and lowering of the arms 81 responsive to movements of the windlassing mechanism 82. In the lowermost position the laterally extending branch 89 of the lower part 85 engages with the stop 63 mounted on the horn 57 and thereby limits downward movement of the said arm 81 and determines the lowermost position thereof, particularly of the lower portion thereof, the upper portion or ends thereof being supported by other means to be described and comprising the stop pins 83 and stops 98. The upper part 84 overlaps the branch 89 as described by the lower end. The mating parts 84 are offset relatively one to the other and the tip ends 91 at the upper end overlap one another, and the interior space conforms to the dimensions of the exterior of the barrel D, and each upper part 84 is provided on the outer side near the upper end with a hump 130.

or projection for engagement with the windlassing mechanism 82. The hump 92 on the part 84 on the side of the fixed horn 57 is sufficiently large to provide a hole 93 for permanently securing one end of a chain M, the other end of which is permanently secured to the shaft 80 by means of a pin 94.

The hump 95 on the part 84 on the side of the movable horn 57 extends upward in the form of an arm to clear the stave tray 67 and has a hole 96 for removably receiving the free end of a chain N, the other end of which is secured to the shaft 80 as described by a pin 94. A hook 97 on the top cross-connecting strip 17 supports the chain N when the same is disengaged from the hole 96. The upper ends of the body portions of the upper parts 84 are provided with an elongated slot 98 engaged with the upper stop pin 83 which permits of to and fro movement of the upper part 84 relatively to the lower part 85 and which limits the drop or downward movement of the said upper part 84 and arm 81 when free from being held by the chains M and N.

The windlassing mechanism 82 comprises the windlass shaft 80 which is mounted in bearings in the end frames 15, has the chains M and N connected to the body portion as described, and at one end is provided with a crank 102, which as shown is operatively connected to the shaft 80 by means of a set of gears 99. The truss hoops F are supported in position convenient for use by means of a rod or wire 100 attached to the top cross connecting strip 17, and bent to form a hook 101 at the lower end. The arm 81 on the side of the movable horn 57 is raised and lowered with the said horn. During the barrel forming operation the trussing arms 81 drop to the lowermost positions permitted by the slots 88 and 98. During the trussing or windlassing operation the shaft 80 serves as a drum for winding up the chains M and N and turning the same by means of the crank 102 operates to draw the upper parts 84 inward and into contact with the sides of the barrel, particularly the tip ends 91, which are slightly rounded on the inner edges, whereby the upper parts 84 ride upwardly, operating to raise the entire arm 81, the lower ends being guided by the slots 88 and shaft 58 until the inner edges bear quite generally on the outer surface of the staves, which are initially spread outwardly beyond the final assembled position, and then further pulling the chains M and N operates to apply the necessary pressure to the circumference of the end of the barrel to bring the staves into edge to edge contact suitably to receive the hoops F.

After the hoops have been placed in position the barrel is completed and the removal of the same is effected by releasing the

chains N, tilting the tray 67 upward, dropping the movable horns 57 and the arms 81 supported thereby, moving the right hand lever H outwardly to bring the sliding coupling sleeve 24 clear of the abutting ends 23 of the shaft parts 21 and 22, freeing the right hand outer end of the left part 21, whereby the said left part may be swung outwardly, supported by the left end by the hinge connection 27 and the platform 28 and shoe 29, sufficiently to permit removal of the completed barrel D axially from the shaft part 21, after the latches 34 are opened permitting the springs 36 to open outwardly and collapse the drum I, releasing the barrel D which may be grasped by the ends and withdrawn from the shaft.

I claim as my invention:—

1. In a barrel making machine, a divided shaft having one of the shaft parts pivotally mounted by one end, and having barrel forming mechanism on the said one of the shaft parts and a sliding sleeve operative to slide over the junction of the two shaft parts to the coupling position and away from such position, and the said barrel forming mechanism comprising a collapsible drum and a collar slidably mounted on the said one of the shaft parts, and means for opening and collapsing the said drum responsive to the sliding movements of the said collar on the said shaft, means for sliding the said sleeve along the said shaft to the coupling position, the said sleeve operative in being moved to such coupling position to engage with the said collar and thereby move the said collar to the position corresponding to the open position of the said drum.

2. A barrel making machine comprising a shaft made up of two parts in alignment, one of the said parts in fixed axial position, the other of the said parts pivotally mounted so as to swing away from the normal axial position and provided with barrel forming devices, and means for connecting and disconnecting the said shaft parts, the said barrel forming devices comprising a collapsible drum, means for coupling the said shaft parts together, and the said means operative to hold the said drum in the extended position.

3. In a barrel making machine, a shaft, a collapsible drum mounted thereon, and lateral forming devices adjacent the said drum, the said drum comprising a plurality of sector members peripherally divided from one another and suitable for being brought alternately to the extended and to the collapsed positions, one part of the said sector members being brought to the extended position by an axial movement in one direction and the other part being brought to the extended position by an axial movement in the opposite direction.

4. in a barrel making machine, a shaft, and a collapsible drum mounted thereon, the said drum being composed of a plurality of sector members, and comprising two peripherally divided sets of alternate members, means for bringing the said members alternately to the extended and to the collapsed conditions, and comprising means connected to each of the said sets and operative to move one of the sets by a movement in one direction and to move the other of the said sets by a movement in the opposite direction. 60
5. In a barrel making machine comprising a shaft and a collapsible drum mounted thereon, means for distending the said drum comprising as one of the elements a sliding collar on the said shaft, the said shaft divided into two parts and a sleeve operative to connect the ends of the shaft parts, an operating lever connected to the said sleeve and operative to move the same to the position for connecting the said shaft, and operative through the said sleeve to move the 70 said collar to the position for distending the said drum.
6. In a barrel making machine having a drum at the middle and inner portion of the barrel and lateral formers at the ends and outer portions of the barrel, the said drum having a generally circular periphery and comprising a plurality of arc-shaped sections at the said periphery, and the said sections being individually spring supported 80 so as to have a limited radial movement permitting of variation of the circumferential dimensions of the said periphery.
7. In a barrel making machine, a collapsible drum composed of a plurality of sector members, and a sliding sleeve, each of the said sector members comprising an arm portion pivotally supported by one end, having a head at the other end, and a segment mounted on the said head, and links connected by one end to the said head and by the other end to the said sleeve, and the said segment mounted on the said head by resiliently connecting means permitting of a limited radial movement of the said segment. 90
8. In a barrel making machine, a collapsible drum composed of a plurality of sector members, and a sliding sleeve, each of the said sector members comprising an arm portion pivotally supported by one end, having a head at the other end and a segment mounted on the said head, and links connected by one end to the said head and by 100
- the other end to the said sleeve, and means of connection of the said segment and head comprising studs and springs mounted thereon and located between the said segment and head. 105
9. In a barrel making machine, a middle drum and a pair of lateral formers, and a stave tray, the said formers comprising each a fixed and a movable member, a loop operative to hold the said movable member in the closed position and the said loop operative as a support for the said stave tray. 110
10. In a barrel making machine having lateral formers, trussing mechanism comprising trussing arms and a windlassing device connected thereto, the said trussing arms supported by the said lateral formers. 115
11. In a barrel making machine, trussing mechanism comprising trussing arms and a windlassing device therefor, the said trussing arms comprising a pair of mating arms, a shaft supporting the lower ends thereof and the said windlassing device connected to the upper end thereof, and the said arms each composed of two parts, connected together by a pivotal connection. 120
12. In a barrel making machine, a pair of trussing arms comprising each a lower arm and an upper arm connected together by a pivotal connection, a shaft, the said lower arm having a slot engaged with the said shaft, and the upper end provided with a slot, and a pin engaged with the said second slot. 125
13. In a barrel making machine, a pair of trussing arms comprising each a lower arm and an upper arm connected together by a pivotal connection, a shaft, the said lower arm having a slot engaged with the said shaft, and the upper end provided with a slot, and a pin engaged with the said second slot, and one of the said arms provided with means for being opened away from the other arm to permit the removal of the barrel. 130
14. In a barrel making machine, trussing mechanism comprising a pair of trussing arms and a windlassing device, means for permitting a limited raising and lowering of the said arms, and the said windlassing device operative to raise the said arms and to forcibly bring them together around the barrel. 135
